UNITED STATES PATENT OFFICE

JAMES J. TRANT AND MARTIN JENSEN, OF CHICAGO, ILLINOIS, ASSIGNEES TO PULLMAN CAR & MANUFACTURING CORPORATION, OF CHICAGO, ILLINOIS, A CORPORATION OF ILLINOIS

CAR WHEEL

Application filed December 6, 1928. Serial No. 324,214.

The invention relates to cast metal car wheels and has for its principal object the production of a wheel of the single plate type having a chilled tread surface.

5 An important object is to form a cast metal wheel having a single plate and an annular cored out portion in the hub area.

Another object is to reduce the amount of metal required in the manufacture of a wheel 10 of a given capacity and to expedite the production thereof.

A further object is to so distribute the metal in the wheel that shrinkage stresses and resultant wheel failure will be reduced to a 15 minimum, or avoided.

The foregoing and other objects are attained by the construction illustrated in the accompanying drawings, in which:

Fig. 1 shows the double plate chilled cast 20 iron wheel heretofore generally used;

Fig. 2 shows the chilled cast iron wheel of the single plate type recently adopted as standard by the American Railway Association;

25 Fig. 3 shows a similar wheel modified in accordance with the invention;

Fig. 4 shows the modified wheel with a portion of the hub broken away to expose the annular cored out portion thereof in accordance with the invention; and

Fig. 5 indicates the manner of supporting the annular core in the hub of the wheel during the process of manufacture.

In the manufacture of the single plate 35 wheel of the type now regarded as standard practice, some difficulty has been found in the production of wheels free from shrinkage cracks. This condition has been due in large measure to the presence of the relatively great 40 mass of metal in the hub area with respect to the thickness of the surrounding plate of the wheel. During the casting process, it was found that the plate portion solidified in the mold more rapidly than did the hub 45 having relatively greater thickness of metal, with the result that the solidification of the hub metal in the mold was retarded by the relatively plastic condition of the metal beneath the hardening surface of the hub and 50 delayed the removal of the casting to the

soaking pit. Heat radiation from the sand mold being relatively more rapid than that from the core metal in the hub mass, that portion of the mold defining the wheel plate area would cool more rapidly than elsewhere 55 and cause the cooling plate metal to shrink and draw metal from the relatively hot mass at the hub as the plate metal solidified.

To overcome the condition inherent in 60 wheels of the type indicated, it is purposed to reduce the mass of metal at the junction of plate and hub as best shown in Figs. 3, 4, and 5, of the drawings, in which 10 represents an annular core traversing the wheel at the junction of plate 11 and hub 12 and displacing the metal formerly occupying that space. Except for the presence of the core 65 holes 13, the contour of the inner face of the present standard single plate wheel has been preserved, only the outer face of the wheel 70 having been modified to accommodate the wheel portion 17 hereinafter referred to.

The plate 11 extends radially from a point 75 traversed by the annular core 10 to the junction 14 with the rim of the wheel. For the major portion of the distance between these points the plate 11 is straight as indicated at a—b, Fig. 3, and dished inwardly towards the core 10 and there bifurcated to straddle the core space with webs 16 and 17 for connecting the plate 11 to opposite ends of hub 12 to resist rail thrust on the flange 18 of the wheel. Obviously, the lack of metal in the 80 core space 10 facilitates the molding of the wheel by the more equable distribution of the metal in the hub with respect to the volume of metal in plate 11, since it permits the uniform cooling and thereby the flow of metal in the plate area at the hub to avoid the stressing of the metal at that point. Thus disposed, the 85 hub metal solidifies rapidly enough to permit the relatively early transfer of the wheel from the mold to the soaking pit before the plate 11 of the wheel has had time to cool in the sand, thereby preventing any undue stressing or drawing down of the metal in the bore of the hub, and the faster the wheels solidify in the mold the sooner they can be removed 90 to the soaking pit after pouring.

Since the time interval between the pouring 100

- of the metal and the transfer of the wheel to the soaking pit must be kept at a minimum in the manufacture of the wheel, the speed with which the hub and adjoining plate metal 5 solidifies and adjusts itself within the critical heat range of the iron before the wheel is removed to the pit becomes important in the production of wheels having the proper physical characteristics.
- 10 Thus constituted, the plate 11 of the wheel may be made thick enough to dispense with the reinforcing ribs 9 disposed radially across the plate of the two-plate wheel formerly used as indicated in Fig. 1. Such ribs formed objectionable T-sections with plate, resulting in the unequal cooling of the casting in the mould and the consequent stressing or initial fracture of the relatively thin metal of the ribs 9 which cooled faster than the greater 15 mass of metal at their bases where they joined the plate. In the present embodiment, because of the absence of core metal in the hub area, the heat generated by the pressing of the wheel upon the axle is rapidly dissipated, preventing the scoring of wheel bore and axle 20 incident to that operation. The annular core space 10 of the wheel is formed by preparing the mold 19 shown in Fig. 5 with an annular sand core 20 supported by chaplets 21 and 25 held from displacement by core prints 22. The inpouring metal 23 flows about the core and prints to provide the core holes 13 and 30 space 10 best indicated in Figs. 3 and 4.
- It will be evident from the foregoing description that the wheel indicated in Figs. 3 35 and 4 is of greater strength because of the more equable distribution of metal and resultant elimination of hub shrinkage strains, and actual tests have indicated a substantial increase in the strength of the wheel as 40 compared with that of the single plate solid hub wheel of like capacity. That because of the more rapid solidification of the wheel in the mold an earlier transfer to the soaking pit is 45 possible while the wheel is yet within the critical heat stage, thereby insuring a more effective annealing of wheels free from initial stresses and incipient hub shrinkage cracks or draws, and other defects. Thru the compensating action of the chiller ring the solidification 50 of the rim mass of the wheel metal is effected as quickly as that of the metal in the hub and plate areas despite the differences in the thickness of the metal in such parts.
- 55 What we claim is:—
1. An article of manufacture comprising a car wheel of the standard A. R. A. type for wrought steel wheels having a single plate and cored hub portion.
- 60 2. An article of manufacture comprising a car wheel of the standard A. R. A. type for wrought steel wheels having a single plate portion and a cored hub section, said plate having bifurcated web portions uniting said 65 plate and hub.
3. A car wheel of the standard A. R. A. type for wrought steel wheels having a cast single plate portion and a cored hub.
4. A car wheel of the standard A. R. A. type for wrought steel wheels having a cast single plate portion and a hub having an annular cored out portion, and spaced web portions connecting said hub and plate.
5. A cast metal car wheel of the standard A. R. A. type for wrought steel wheels having a dished single plate portion and a hub, and an annular cored out portion intermediate said hub and plate.
6. A cast metal car wheel of the standard A. R. A. type for wrought steel wheels having a straight single plate portion dished inwardly from the tread and a hub, and an annular cored out portion intermediate said hub and plate.
7. In a cast metal wheel of the standard A. R. A. type for wrought steel wheels, the combination comprising a single plate portion and a cored hub, and a plurality of diverging web portions defining an annular core about said hub and uniting said hub and plate.
8. In a cast metal car wheel of the standard A. R. A. type for wrought steel wheels, the combination comprising a single plate portion dished inwardly from the tread and including the hub, and a plurality of diverging web portions defining an annular core about said hub.
- In witness whereof we have hereunto set our hands this 22nd day of November, 1928.
